UNITED STATES PATENT OFFICE.

ALFRED C. SCHMOHL, OF BEAVER FALLS, PENNSYLVANIA, ASSIGNOR TO KOPPEL INDUSTRIAL CAR AND EQUIPMENT COMPANY, OF PITTSBURGH, PENNSYLVANIA, A CORPORATION OF PENNSYLVANIA.

DUMP CAR.

Application filed July 1, 1926. Serial No. 119,853.

This invention relates to railway dump cars and more particularly to that type of dump car having a tilting body and has for an object the provision of resilient means for retarding the tilting movement of the body.

Another object of the invention is to provide a dump car having a tilting body, with means for permitting a free initial tilting movement of the body and for retarding the final tilting of the body.

A further object of the invention is to provide the hinge between the tilting body and the underframe of a railway dump car with means for retarding the tilting movement of the body.

These and other objects will be apparent from the following description.

Referring to the drawings in which like reference characters refer to like parts, Fig. 1 is a cross sectional view of a dump car embodying the invention, the full lines showing the body of the car in its righted position and the dot and dash lines showing the body tilted to one side to its discharging position; Fig. 2 is an enlarged cross sectional view of a portion of the car showing the hinge for the body in detail when the body is in its righted position; Fig. 3 is an enlarged longitudinal sectional view of a portion of the car showing the hinge in side elevation when the body is in its righted position and Fig. 4 is a cross sectional view similar to Fig. 2, but showing the several parts of the hinge in their positions when the car body is tilted.

Referring now in detail to the drawings the reference character 1 indicates the underframe of the car and 2 the car body, which body is mounted on the underframe in such a manner that it can be tilted to one side or the other to discharge the lading carried thereby.

The underframe and body may be of any suitable construction and are connected together through the medium of hinges 3 which hinges permit the body to tilt and move bodily toward one side or the other.

Each of the hinges 3 comprises a part 4 which is secured to the underframe and a part 5 which is secured to the car body. The part 4 extends upwardly from the underframe and the upper outer surface thereof is provided with a centrally arranged depression 6. At each side of this part the upper outer surface thereof is curved as indicated by the reference character 7.

The part 5 depends downwardly from the body of the car and is provided with spaced lower portions 8 which are adapted to overlap the sides of the part 4. Between these lugs a web 9 is provided having its sides 10 curved downwardly to correspond with curved portions 7 of the part 4. The spaced portions 8 are provided with openings through which a pin 11 passes, such pin, between the portions 8 being adapted to seat in the recess 6 of the part 4 and form a pivot for the car body during the partial tilting or righting of the body. This pin extends through the openings in the portions 8 and beyond such portions and at each one of its ends has loosely mounted thereon an eye bolt 12, the lower end portion of which extends through a cover plate which is secured to the center sills of the underframe. The bolts 12 also pass through a block 13 arranged below the cover plate and the part 4. In the present embodiment of the invention the block 13 directly engages the cover plate secured to the center sills, but it will be understood that in some cases the cover plate may be omitted, in which cases the block will directly engage the part 4 of the hinge.

Below the block 13 each bolt passes through a spring 14 and a washer 15, which washer is held on the bolt by a nut 16. The upper end of this spring seats on the underside of the block 13 while the lower end seats on the upperside of the washer 15. It will here be noted that the bolts 12, washers 15 and nuts 16 are free to move upwardly and downwardly and that the block 13, due to its engagement with the underframe, or with the part 4 of the hinge, is held against up-

ward movement, thus any upward movement of the bolts will cause the springs 14 to compress.

When the car body is in its righted position the pins 11 of the parts 5 are seated in the depressions 6 of the parts 4 and these pins support the body and any weight carried thereby.

Assuming the car body being tilted or moved to one side toward discharging position from its righted position, the pin 11 of each hinge forms an axis around which the body rotates until such time as one of the curved portions 7 of the part 4 is engaged by one of the curved sides 10 of the part 5 when the weight of the body will be transferred from the pin 11 to the parts 4 and 5 directly and by a continued movement of the body, the engagement of the parts 4 and 5 will cause the body and pin 11 to be elevated to some extent and moved laterally at the same time. As the pin 11 is moved upwardly the eye bolts 12 are moved with it, thus causing the springs 14 to be compressed, thus retarding the momentum of the body as it is being tilted. It will here be noted that besides retarding the momentum of the body the springs 14 will also, to some extent, assist in righting the body. It will be further noted that instead of the springs 14 any other suitable retarding device may be used.

It will be understood that changes may be made in the details and arrangement of the several parts forming the invention without departing from the spirit and scope of the appended claims.

Having thus described the invention what I claim as new and desire to secure by Letters Patent is:—

1. In a dump car, an underframe, a tilting body mounted on said underframe and resilient means at the longitudinal center line of the car and between said body and underframe adapted to retard the momentum of said body as it is being tilted.

2. In a dump car, an underframe, a tilting body, a hinge for said body, and means attached to a movable part of said hinge and engaging a stationary part of said underframe for retarding the momentum of said body as it is being tilted, said means being located at the longitudinal center line of the car.

3. In a dump car, an underframe, a tilting body, a hinge for said body comprising a stationary part attached to said underframe and a movable part attached to said body, and means for retarding the momentum of said body when it is tilted, said means being connected with said movable part and to a stationary part on said underframe and located at the longitudinal center line of the car.

4. In a dump car, an underframe, a tilt-

ing body, a hinge for said body, a pin for said hinge forming a pivot for said body during a partial tilting thereof, and means forming a pivot for said body during the rest of the tilting movement of said body, and means connected with said pin and said underframe for retarding the momentum of said body when the first mentioned means forms a pivot for said body.

5. In a dump car, an underframe, a tilting body, a hinge for said body comprising a movable part attached to said body and a stationary part attached to said underframe, means on said parts adapted to cooperate to form a pivot for said body during a partial tilting of the body, and means on said parts adapted to cooperate to form a pivot for said body during the rest of the tilting movement of the body, and means for retarding the momentum of said body when the last mentioned means are in cooperation, said momentum retarding means being inoperative when the first mentioned means on said parts are in cooperation.

6. In a dump car, an underframe, a tilting body, a hinge for said body comprising a movable part on said body and a stationary part on said underframe, a pin in said movable part adapted to cooperate with said stationary part to form a pivot for said body during a partial tilting of said body, and means on said parts adapted to cooperate to move said body and pin upwardly during the rest of the tilting movement, and means connected with said pin for retarding the momentum of said body.

7. In a dump car, an underframe, a tilting body mounted on said underframe, a hinge for said body comprising a movable part and a stationary part, a member connected with said movable part, and a resilient member between said member and underframe adapted to retard the momentum of said body as it is being tilted.

8. In a dump car, an underframe, a body tiltably mounted on said underframe, a hinge for said body having a movable part connected with said body, a stationary part connected with said underframe, and resilient means between said movable part and said underframe for retarding the momentum of said body as it tilts.

9. In a dump car, an underframe, a body tiltably mounted on said underframe, a hinge for said body having a movable part secured to said body and a stationary part secured to said underframe, a pin extending through said movable part, being movable upwardly during a partial tilting of the body, members attached to the ends of said pin and extending downwardly through a portion of said underframe, a bearing block loosely mounted on said members and extending beneath said stationary part of said

hinge, washers on said members between said washers and bearing block adapted to retard the movement of said body when said pin is moved vertically.

5 10. In a dump car, an underframe, a body tiltably mounted on said underframe, a hinge for said body having a movable part attached to said body and a stationary part secured to said underframe, said hinge pro-

viding a central pivot for said body during 10 an initial tilting of the body and a side pivot for said body during the final tilting movement of the body and means attached to said movable part and to said underframe adapted to retard the momentum of said 15 body during its final tilting movement only.

In testimony whereof, I affix my signature.

ALFRED C. SCHIMÖHL.
